UNITED STATES PATENT OFFICE

162,825

TEXTILE FABRIC OR SIMILAR ARTICLE

Marion R. Hamre, Oceanside, N. Y.

Application April 18, 1950, Serial No. 9,296

Term of patent 7 years

(Cl. D92—1)

To all whom it may concern:

Be it known that I, Marion R. Hamre, a citizen of the United States, residing in Oceanside, county of Nassau, and State of New York, have invented a new, original, and ornamental Design for a Textile Fabric or Similar Article, of which the following is a specification, reference being had to the accompanying drawing, forming part thereof.

In the drawing, the figure is a face view of a textile fabric, showing my new design.

A design unit is outlined by broken lines. Said unit is repeated over the fabric as indicated.

I claim:

The ornamental design for a textile fabric or similar article, as shown and described.

MARION R. HAMRE.
